UNITED STATES PATENT OFFICE.

CARL POSEN, OF OFFENBACH-ON-THE-MAIN, GERMANY.

FASTENING FOR POCKET-BOOKS, &c.

SPECIFICATION forming part of Letters Patent No. 234,805, dated November 23, 1880.

Application filed September 9, 1880. (Model.)

To all whom it may concern:

Be it known that I, CARL POSEN, of Offenbach-on-the-Main, Germany, have invented a new and useful Improvement in Fastenings for 5 Pocket-Books and other Articles, of which the following is a specification.

Figure 1 is a face view of the improvement shown as applied to a pocket-book. Fig. 2 is a sectional elevation taken through the line x x , Fig. 1, shown as fastened. Fig. 3 is a sectional elevation taken through the line x x , Fig. 1, shown as unfastened. Fig. 4 is a plan view of the base-plate. Fig. 5 is a sectional elevation of the base-plate, taken through the line y y , Fig. 4. Fig. 6 is a sectional elevation of the spring and spring-plate, taken through the line z z , Fig. 7. Fig. 7 is a plan view of the spring and spring-plate. Fig. 8 is a perspective view of the keeper for the spring. 20 Fig. 9 is a plan view of the under side of the fastening-plate and its spring-hinge. Fig. 10 is a side elevation of the knob and its shank. Fig. 11 is a section of the knob-shank washer.

Similar letters of reference indicate corresponding parts.

The object of this invention is to furnish fastenings for pocket-books and other articles so constructed that they may be easily and conveniently fastened and unfastened, and 30 will not be liable to get out of order.

The invention consists in constructing a pocket-book fastening of a base-plate to support the operating parts, and provided with lugs and an opening in its rear part, the spring 35 carrying a plate and having a catch, a lock-plate having a pivot-socket, a catch, and an opening in its forward part, a pivot for hinging the lock-plate, a spiral spring for raising the lock-plate, and a knob to engage with the 40 lock-plate, as will be hereinafter fully described.

A represents the base-plate, in which, at one end, is formed a semicircular opening, having a notch in the middle part of its straight side. 45 Across the middle part of the base-plate A is formed a flange, B, having a notch in its center, and in its side edges, at the rear side of the flange B, are formed lugs C to receive the pivot of the hinge. The part of the base-plate 50 A in the rear of the flange B is covered by the

semicircular plate D, which has a downwardly-projecting flange around its curved edge.

To the lower side of the plate D is riveted the spring E, which is bent downward to pass through the aperture in the base-plate A, is 55 then bent forward and upward, and its forward end is riveted to the forward part of the lower side of the said base-plate. The base-plate A is secured to the body of the pocket-book by clinched nails or points, and the spring 60 E is so formed that the spring-plate D may be held a little above the base-plate A, as shown in Figs. 2 and 3. The outward movement of the plate D is limited by the keeper F, which passes around the spring E just in front of its 65 shoulder, and the ends of which are clinched in the body of the pocket-book.

To the spring E, a little in front of its shoulder, is attached a catch, G, to engage with a similar catch, H, attached to the middle part 70 of the pivot-socket I of the lock-plate J. The pivot-socket I is made of such a length as to fit between the lugs C of the base-plate A, and its cavity is made of such a size as to receive the pivot K and a spiral spring, L, coiled upon 75 the said pivot K. The ends of the pivot K are riveted in holes in the lugs C. One end of the spiral spring L is secured to the socket I, and its other end is secured to one of the lugs C in such a position that the tension of 80 the said spring L will hold the lock-plate J raised, as shown in Fig. 3.

In the forward part of the lock-plate J is formed a hole, M, to receive the knob N, the shank O of which is passed through the flap of 35 the pocket-book and through the arms of a U-plate, P, placed upon the said flap, and is riveted down upon the inner arm of the said U-plate P, so that the said knob will be held securely in place. The outer arm of the U-plate 90 P has an outwardly-projecting rim or flange formed around it, forming a recess to receive the lock-plate J, so that the fastening can be unfastened only by pressing upon the trip-plate D to disengage the catches G H and 95 allow the spring L to raise the lock-plate J. This construction prevents any one from opening the fastening by raising the lock-plate J instead of pressing down the trip-plate D.

The knob N is made with a convex top and 100

straight sides, as shown in Fig. 10. With this construction the pocket-book is fastened by pressing the lock-plate J down upon the knob N, the convex top of which causes it to center itself and enter the hole M, the catch H at the same time striking the catch G, forcing the spring E downward and passing the said catch G. The catch G is raised by the elasticity of the spring E, engages with the catch H, and thus locks the fastening.

The fastening is unlocked by pressing the spring-plate D downward, which withdraws the catch G from the catch H and allows the lock-plate J to be raised by the elasticity of the spiral spring L.

Having thus described my invention, what I claim as new, and desire to secure by Letters Patent, is—

1. A pocket-book fastening constructed substantially as herein shown and described, consisting of the base-plate A, having flange B, lugs C, and an opening in its rear part, the spring E, carrying plate D, and catch G, the lock-plate J, having pivot-socket I and catch H, the pivot K, the spiral spring L, and the knob N, as set forth.

2. In a pocket-book fastening, the combination, with the base-plate A and the lock-plate

J, of the two springs E L and the two catches G H, substantially as herein shown and described, whereby the lock-plate is held closed and is opened, as set forth.

3. In a pocket-book fastening, the combination, with the base-plate A, the spring-plate D, and the lock-plate J, of the spring E and the two catches G H, whereby the lock-plate is held closed, as set forth.

4. In a pocket-book fastening, the combination, with the base-plate A, having lugs C, the lock-plate J, having socket I, and the pivot K, of the spiral spring L, substantially as herein shown and described, whereby the lock-plate J is raised when released, as set forth.

5. In a pocket-book fastening, the combination, with the knob N, of the U-plate P, having an outwardly-projecting rim around the edge of its outer arm, substantially as herein shown and described, to form a recess to receive the lock-plate J and prevent the fastening from being unfastened by raising the said lock-plate, as set forth.

CARL POSEN.
